CHUSETTS.**

SHOE MANUFACTURE.

Application filed January 29, 1926. Serial No. 84,806.

This invention relates to reinforcing tape for shoe uppers or portions thereof such as vamps. Reinforcing tape for this purpose has commonly consisted of ordinary fabric tape with the warp and weft parallel and at right angles to its edges. Such tape is usually woven in a separate strip with a selvaged edge or cut straight with the warp out of duck, lawn or similar fabrics and in either of these forms is practically inelastic; consequently, when in accordance with ordinary practice, it is adhesively secured to a portion of an upper, the tape is often not adapted to yield sufficiently to accommodate itself to the stretch given the upper by the lasting operation and therefore it has a tendency to draw away from the leather portion of the shoe and to form undesirable bunches upon the inner side of the shoe, thus depriving the shoe of the reinforcing effect of the tape.

When reinforcing tape of this type is to be given any considerable transverse curvature in its own plane it has been necessary to cut or overlap portions of the tape, since otherwise its inelasticity would prevent its being secured in close relation to the surface of the leather, and, if the tape was not arranged in this manner, one of its edges would tend to pull away from the leather and to wrinkle or fold. The present invention is designed to obviate the foregoing difficulties by providing a reinforcing tape which possesses a degree of elasticity which may be similar to the elasticity of the leather itself and which will thus enable it readily to conform to the lasting operation and also permit it to remain in close contacting relation with the surface of the leather, although having been given a considerable transverse curvature in its own plane.

In the practical embodiment of my invention the elasticity of the tape as prepared may be varied within fairly wide limits. If the tape is too yieldable it will form but a slight reinforcement for the upper, while if it is comparatively inelastic, it will tend to bunch and draw away from the lasted portion of the upper, as has been described. However, if the tape is provided with a degree of elasticity somewhat similar to that of the upper itself, it has been found to be

satisfactory in use constituting suitable reinforcing means for any portion of the shoe to which it is applied and being flexible enough to follow the curved edges of the reinforced portions. In attempting to obtain a reinforcing tape having such qualities I have found that tape cut upon a bias to the warp and weft of the fabric and pre-stretched before use, affords a suitable degree of elasticity. If, for example, a strip of material which has been cut on the bias is stretched a moderate amount, it will have little or no elasticity or tendency to return to its original form. However after it has been stretched to a still greater extent, it is found to possess a quite appreciable degree of permanent elasticity, which may be varied within certain limits.

Furthermore by cutting the tape out at a bias to the fabric and leaving its edges unfinished with free severed ends of the thread exposed and pre-stretched before use, a tape is obtained which is especially adapted to transverse bending in its one plane without wrinkling or folding while at the same time having a degree of elasticity comparable to that of leather.

The present invention therefore concerns the provision of tape of this type and its combination with portions of the shoe upper.

In the drawings,

Fig. 1 is an elevational view of a portion of a band used for forming the improved type of tape.

Fig. 2 is a similar view of a portion of the band after it has been stretched;

Fig. 3 is a view of a section of the band cut into tape;

Fig. 4 shows a shoe vamp with the improved binding tape affixed thereto; and

Fig. 5 is a side elevation of a shoe, showing in dotted lines the upper edge of the shoe reinforced by the tape.

In order to provide reinforcing tape having a desirable degree of elasticity for the purpose designated above, I prefer to take a band 1 of woven material which will have its width equal to the width of a number of separate tapes and have its warp and web diagonally disposed in relation to its edges so that it possesses a rather high degree of elasticity. This band may be cut from duck,

- 2
- twill, lawn or similar fabrics such as are ordinarily used for reinforcing tape. To obtain this band a wide piece of fabric having its edges selvaged is cut into a series of 5 diagonal strips, the selvaged ends of these strips being sewed to each other to form the long continuous band 1, which may be conveniently rolled. The selvaged ends of the strips are adapted to be sewed to each other 10 without folding, the flat seams thus formed being of unobjectionable thickness when occurring in the finished tape. The band 1 is then preferably fully stretched in order to give it a suitable elasticity or tendency to return 15 to normal form after restretching in use and is then cut along parallel lines 5 (Fig. 2) into separate strips forming individual strips of reinforcing tape 2, as indicated in Fig. 3.
- 20 When preparing large strips for the making of this pre-stretched bias reinforcing tape, it has been found preferable to cut the diagonal sections from unsized fabric, then sew these diagonal strips together on the 25 selvaged edges, thus forming a wide band of any desired length, as for instance 500 or 1000 yards. The wide web thus formed is then passed through a sizing bath and thence through a calender machine with 30 multiple heated rolls. While placing a drag or tension on the drying fabric which has left the massaging bath the operation of the multiple rolls of the calender machine takes 35 all of the longitudinal stretch out of the web which thus leaves the calender machine dry, smoothly ironed and thoroughly pre-stretched, retaining only the amount of elasticity desired.
- This pre-stretching operation has the effect 40 of shrinking the band in width, as for instance a biased band 54 inches wide may be reduced to approximately 36 inches in width and the pre-stretching has the effect of drawing the right angled weave into a diagonal form in the manner illustrated in 45 Figs. 1 and 2 of the drawings, thus the gain in length from the pre-stretching operation being much less proportionally than the shrinkage in width and the thickness of the cloth being increased. The sizing bath contributes to the stretching operation because the fabric is wet when stretched, and also has a desirable effect of setting the bias 50 stitching on the selavage edges which strengthens the stitching to hold the joints in the narrow tape as afterwards cut and also prevents the selavage edges from projecting from the fabric.
- 55 It is to be understood that the tape may be stretched in separate strips rather than being cut from a wide band which has been stretched in the manner described. Such a method, however, has the disadvantage of tending to break away thread ends at the 60 edges of the tape.

Reinforcing tape of this type is applied to the leather portions of the upper by the use of cement. Plastic or semi-moist cement of the type which remains plastic indefinitely and is susceptible of use without the application of heat or moisture is preferable in this location and therefore after the tape has been prepared as indicated above, I propose to run it through suitable apparatus for the application of plastic cement to one of its 70 faces. However, if desired the tape may be passed through a machine for applying cement thereto and for stretching the tape at the same time or in consecutive operations.

The tape is then ready to be applied to 80 portions of shoe uppers such as a vamp 3 having a curved edge 4, said curvature being in the plane of the leather. The tape is adapted to be adhesively affixed to the edge of the vamp, to have all portions of its adhesive surface in intimate contact with the marginal portion of the vamp closely parallel to the curved edge 4, and to flex in accordance with the shape imparted to the 85 vamp during lasting.

Fig. 5 illustrates the use of tape of this type in another location, the tape being shown as reinforcing the upper margin of a shoe or slipper 6. This tape may also be used in many other analogous locations in accordance with the cut and design of the particular shoe, slipper or the like.

While tape prepared and applied to the shoe portions in the manner described is preferred, obvious modifications and optional arrangements of steps in the preparation of reinforced shoe uppers are regarded as within the purview of this invention. For example, the plastic cement may be applied to the tape either before, after, or simultaneously with the stretching operation, and the latter operation may take place when the tape is cut in separate strips if desired, or the plastic cement may be omitted and the tape secured to the leather etc. with wet cement.

It is to be understood that reinforcing tape of this character is not only useful in leather upper portions, such as vamps, but may be also used for fabric uppers or in any 111 location where reinforcing tape has ordinarily been found useful, or in fact in other locations where the lack of elasticity and conformability in ordinary tape has previously been an obstacle to its satisfactory use.

I claim:

1. Reinforcing tape for a portion of a shoe upper, comprising a fabric strip formed with its warp and weft diagonally disposed in relation to its edges and being pre-stretched to give it a degree of elasticity similar to that of the upper.

2. The combination of a portion of a shoe upper and a woven reinforcing tape adhesively secured thereto, said tape being cut

and pre-stretched on the bias to have a degree of elasticity similar to that of the upper.

3. The combination of a leather portion 5 of a shoe upper having an edge curved in the plane of the leather and a pre-stretched bias reinforcing tape adhesively secured thereto, said tape being provided with a degree of elasticity permitting its application 10 in flat contacting relation with the margin of said upper portion adjacent to and substantially parallel to said curved edge.

4. Reinforcing tape for a shoe upper comprising a strip of woven fabric with its 15 warp and weft diagonally disposed in relation to its edges, said tape being pre-stretched and having a coat of plastic cement applied to one of its sides.

5. The method of preparing reinforcing

tape for a shoe upper, comprising the cutting of a band of woven fabric with its edges diagonally disposed in relation to the warp and weft of the fabric, stretching the band to give it the desired degree of elasticity, and cutting it into a plurality of parallel 25 strips and applying plastic cement to one side of the strips.

6. The method of preparing a reinforcing tape for a shoe upper, including cutting a strip of fabric obliquely to the warp and 30 weft thereof, stretching the same to give it the desired degree of elasticity, and applying plastic cement to one side of the stretched material.

Signed by me at Boston, Massachusetts,
this 31st day of December 1925.

HAROLD A. EVANS.
